UNITED STATES PATENT OFFICE.

CAROLINE BARD TOMPKINS, OF JERSEY CITY, NEW JERSEY.

SLATE.

SPECIFICATION forming part of Letters Patent No. 723,340, dated March 24, 1903.

Application filed May 9, 1902. Serial No. 106,557. (No model.)

To all whom it may concern:

Be it known that I, CAROLINE BARD TOMPKINS, a citizen of the United States of America, residing at Jersey City, in the county of Hudson and State of New Jersey, have invented 5 an Improvement in Slates, of which the following is a specification.

My invention relates to a school-slate especially adapted for young pupils as well as for 10 the blind.

The slate preferably has a black surface on one side and a white surface on the other side. The frame of the slate is made with recessed receptacles for holding articles used 15 in connection with a slate—such as pencils, pens, penholders, &c.—and these recessed receptacles are made with undercut grooved edges for sliding covers whose side edges correspond with the undercut grooved edges of 20 the receptacles, so that the surfaces of the covers are flush with the faces of the slate-frame. Upon the exposed surfaces of the sliding covers I apply the letters of the alphabet, numerals, or other characters, words, or 25 designs. I prefer to attach to one of the sliding covers a timepiece-dial with hands. I make use of a straight-edge or ruler whose ends are inserted into and slide in longitudinal grooves provided therefor in the inner 30 opposite edges of the side members of the slate-frame. The straight-edge or ruler carries a strip of sponge, chamois, or other suitable material forming an eraser or slate-cleaner. There is also attached to the 35 straight-edge or ruler at its center a pencil-sharpener. On one side of the slate-frame are preferably provided corner buffers or pads.

In the drawings, Figure 1 is a plan view of one side of the slate with two of the sliding 40 covers partly withdrawn. Fig. 2 is a plan view of the opposite side of the slate. Fig. 3 is a longitudinal section at the line $x-x$ of Fig. 1, and Fig. 4 is a cross-section at the line $y-y$ of Fig. 1.

45 The slate a preferably has one surface black for the use of slate-pencils and the other surface white for the use of lead-pencils. The slate is held by a frame composed of four members $b b' b'' b'''$. In the members of the 50 frame are provided recessed receptacles c for such articles as pencils, pens, penholders, &c., and the recessed receptacles in the side mem-

bers are longer than those in the end members of the frame, but are all of approximately the same depth. These recessed receptacles are preferably all in one surface of the frame. These recessed receptacles c are made with undercut grooved edges to receive the sliding covers $e e' e'' e'''$, whose side edges correspond thereto, so that the surfaces of the covers are flush with the face of the slate-frame. These covers are preferably made of wood, but may be made of hard rubber, celluloid, metal, or any desired material. The letters, figures, or characters upon the surfaces of the sliding covers $e e' e''$ are conveniently placed for pupils to study and to copy upon the slate, either singly or in groups forming words or numbers. These letters, figures, or characters are preferably raised 70 or in relief, which permits of their shape being followed by the touch of the fingers of blind pupils, and such letters, figures, or characters may be glued or otherwise attached to the covers.

75 The sliding cover e''' is preferably provided with a timepiece-dial and hands f . The dial is secured to the cover e''' by glue or in any other desired manner, and the hands are separate, but are fixed to the center eyelet or pin, so that they cannot become accidentally detached, but may be moved around the dial by hand in learning to tell time. The dial is preferably provided with an upturned rim or annular flange g to prevent injury to the 80 hands.

Corner buffers or pads h are preferably secured to the slate-frame upon the side opposite to that having the covers. These pads are of any shape or thickness desired, and 90 serve both as pen-wipers and to prevent the slate marking the desk or making a noise when laid down on the desk.

In the inner opposite edges of the frame members $b b'$ there are longitudinal grooves 95 $i i$, which receive the ends 2 2 of a straight-edge or ruler k , and in which grooves the straight-edge or ruler k may be slid up and down over the surface of the slate a . The grooves $i i$ are cut in the frame members 100 slightly above the surface of the slate, so that the straight-edge or ruler will not scratch the slate while being passed up and down in the grooves, but at the same time it will be

sufficiently near the surface of the slate, so that true and parallel lines may be drawn thereon. The end portions 22 of the straight-edge or ruler which slide in the grooves *i i* 5 may be made narrower than that portion of the straight-edge or ruler which passes over the slate, such wider portion having a folded or bent-over portion *l*, as shown in the section, Fig. 3, for the purpose of holding a piece 10 of sponge, chamois, or other suitable material *m* for erasing pencil-marks or cleaning the slate as the straight-edge or ruler *k* is slid down in the grooves *i i*, thus leaving a clean surface above it for writing or drawing. It will be noticed that the eraser can be kept from touching the surface of the slate as the straight-edge or ruler is slid up or down in the grooves, if desired, by simply 15 lifting it slightly. I prefer to make the straight-edge or ruler *k* of metal having sufficient strength and spring to prevent its being easily bent out of shape and to retain it within the grooves in a line parallel with the top and bottom members of the frame. 20 25 I also prefer that its surface be provided with graduated marks. I also prefer to attach to the straight-edge or ruler *k* at its center by suitable means a pencil-sharpener *n*, which also serves the purpose of a handle for sliding the straight-edge or ruler up or down in the grooves *i i*, and further forms a convenient holder for a pencil.

I claim as my invention—

1. A slate having a frame with longitudinal 35 grooves in the inner opposite edges of two of the frame members, a straight-edge or ruler having its ends fitted within and adapted to slide in said grooves, and a slate-cleaner attached to and carried by said straight-edge 40 or ruler, substantially as specified.

2. A slate having a frame with longitudinal grooves in the inner opposite edges of two of the frame members, a straight-edge or ruler having its ends fitted within and adapted to 45 slide in said grooves, said end portions being narrower in width than the other part of the straight-edge or ruler, such wider portion

being folded over longitudinally on one edge with a strip of soft material clamped between the fold forming a slate-cleaner, substantially as specified.

3. A slate having a frame with longitudinal grooves in the inner opposite edges of two members of the frame, a straight-edge or ruler having its ends within said grooves, a slate-cleaner attached to and carried by said straight-edge or ruler, and a pencil-sharpener fastened to the straight-edge at its center, substantially as specified.

4. A slate having a frame with recessed receptacles in the several members of the frame having undercut grooved edges, sliding covers for such receptacles whose side edges correspond to the said undercut grooved edges, so that the covers are flush with the slate-frame, two members of the frame each having a longitudinal groove in the inner edge, a straight-edge or ruler with its ends within and adapted to slide in said grooves, and a slate-cleaner attached to and carried by said straight-edge or ruler, substantially as specified.

5. A slate having a frame with recessed receptacles in the several members of the frame having undercut grooved edges, sliding covers for such receptacles whose side edges correspond to the said undercut grooved edges, so that the covers are flush with the slate-frame, two members of the frame each having a longitudinal groove in its inner edge, a straight-edge or ruler with its ends within and adapted to slide in said grooves, said end portions being narrower in width than the other part of the straight-edge or ruler, such wider portion being folded over longitudinally on one edge with a strip of soft material clamped between the fold forming a slate-cleaner, substantially as specified.

Signed by me this 7th day of May, 1902.

CAROLINE BARD TOMPKINS.
